(57) **CLAIM**

The ornamental design for a roof gutter rainwater collector, as shown and described.

DESCRIPTION

FIG. 1, is a front perspective view of a roof gutter rainwater collector showing my new design;

FIG. 2 is a front elevation view thereof;

FIG. 3 is a side elevation view thereof, the other side being the same;

FIG. 4 is a rear elevation view thereof;

FIG. 5 is a top plan view thereof; and,

FIG. 6 is a bottom plan view thereof.
